(57) **ABSTRACT**

A strapless multi-use garment comprises an upper garment portion designed to cover an area above waist of a user having a front portion and a rear portion, a gathered skirt having a front portion and a rear portion attached with the upper garment portion, a waist band attached at a top portion of the gathered skirt, a plurality of front panels attached at the front portion of the gathered skirt, a plurality of rear panels is attached at the rear portion of the gathered skirt and at least one fastening means. The plurality of front panels and the plurality of rear panels, extending downwardly from the waist band, are adaptable for multiple configurations that allow the multi-use garment to be worn in a wide range of stylish designs in different occasions.

MULTI-USE GARMENT**CROSS-REFERENCE TO RELATED APPLICATIONS**

This application is a continuation of U.S. patent application Ser. No. 13/672,422, filed Nov. 8, 2012, which claims the benefit of U.S. Provisional Patent Application No. 61/596,646, filed on Feb. 8, 2012, which are hereby incorporated by reference herein in their entireties.

STATEMENT REGARDING FEDERALLY SPONSORED RESEARCH AND DEVELOPMENT

Not Applicable.

FIELD OF THE DISCLOSURE

The present disclosure relates generally to garments, and more particularly, to a strapless multi-use garment having a plurality of panels adaptable for multiple configurations that allows the multi-use garment to be worn in a wide range of stylish designs.

DISCUSSION OF RELATED ART

A wide variety of stylish multi-use garments have been developed in the art. The multi-use garments enable a single garment to be worn in different configurations. This is because the multi-use garments can be configured into multiple styles thereby allowing a single dress to be used in different occasions. The multi-use garments remove the burden of storing multiple articles of clothing for different styles and occasions. Usually, multi-use garments are mainly manufactured for women. The multi-use garments can be worn anywhere and converted to other versatile designs. However, conventional multi-use garments have considerable drawbacks. For example, most of the multi-use garments do not possess an aesthetic appearance. Such garments cannot be quickly converted to other designs and require more manipulations for the conversions. Since these garments have different functions, they will be very bulky, have complex construction and be less portable.

Most of the multi-use garments are designed in such a way that they can be styled in a limited number of ways. Also, the multi-use garments available today are not suitable for brides as they are not very attractive. Another drawback for the existing multi-use garments is that they are fabricated in stretch material and have more straps on their shoulder parts. This causes discomfort to the user. Therefore, it would be desirable to provide an improved strapless multi-use garment that do not require extra support to stay on user's body.

U.S. Pat. No. 8,214,923 issued to Lee on Jul. 10, 2012 provides a multi purpose garment that can be worn in a variety of configurations on different parts of the body and for a variety of occasions. The garment includes a first sheet of material and a second sheet of material, which is positioned opposite the first sheet of material. The first and second sheets of material are secured to one another at or near two opposite ends of the sheets of material. The two other opposite ends of the sheets of material are open to allow a part of the body to pass through at least one of the openings. At least one of the open ends has a securing device positioned along at least a portion of the opening that may securely close at least a portion of the respective opening to

secure the garment about the person. However, the multi-purpose garment does not provide aesthetic appearance.

Similarly, as taught in U.S. Pat. No. 4,142,253 issued to Roscoe on Mar. 6, 1979 provides a multi-purpose or multi-functional and multi-style garment which has a generally tubular structure or configuration, having in the upper section thereof at least two integral tie sections, the locus of the profiles of the tie sections being of generally triangular configuration and the length of the tie sections being greater than the radius of the tubular structure, whereby the garment is adapted to multiple functions and styles and modular coordination with accessories. A garment of this invention can be made from a tubular blank, a planar blank folded upon itself, or from a flat unfolded piece of textile material. The tie sections integrated to the multi-purpose garment provide discomfort to the user.

In addition, U. S. Pat. No. 20090300817 issued to Fata on Dec. 10, 2009 describes a multi-use and multi-style garment is shown from a single piece of fabric, having a tubular main portion having both anterior and posterior edges when viewed in elevation, the tubular main portion being adapted to surround desired portions of the body of the wearer; can be manipulated in different ways depending on both the desired type and style of clothing; a vertical slit extending downwardly on the anterior edge of at least one side of the tubular main portion to allow for mobility when the garment is worn by the wearer; the shorter the garment to the point of substantially being a blouse, and the longer the diameter the longer the garment to the point of substantially being a dress; when the opposing extensions are not crisscrossed and tied around the waist of the wearer, the garment is substantially a skirt. The multi purpose garment does not provide aesthetic appearance and it is not versatile for usage in different occasions.

Therefore, there is a need for a simple, stylish and aesthetic multi-use garment. Such a needed multi-use garment would be quickly converted to other designs. Such a device would be lightweight and portable. Moreover, the needed device would possess an attractive appearance and would be suitable for brides. Further, the needed device would be converted into a large number of versatile stylish designs and be strapless. Finally, the needed device would be fabricated from fine quality material and would not require additional support to stay on the user's body. The present disclosure accomplishes these objectives.

SUMMARY OF THE DISCLOSURE

The present embodiment provides a strapless multi-use garment. The strapless multi-use garment comprises an upper garment portion, a gathered skirt, a waist portion, a waist band attached at a top portion of the gathered skirt, a plurality of front panels, a plurality of rear panels and at least one fastening means. The upper garment portion has a front portion and a rear portion is designed to cover an area above the waist of a user. The gathered skirt is attached to the upper garment portion and has a front portion and a rear portion. The plurality of front panels is attached at the front portion of the gathered skirt and extends downwards from the waist band. The plurality of rear panels is attached at the rear portion of the gathered skirt and extends downwards from the waist band. The at least one fastening means extends downwardly along the rear portion of the upper garment portion and the rear portion of the gathered skirt. The at least one fastening means allows to secure the strapless multi-use garment firmly on the user's body.

The plurality of front panels and the plurality of rear panels are adaptable for multiple configurations that allows the multi-use garment to be worn in a wide range of stylish designs in different occasions. The plurality of front panels and the plurality of rear panels are pleated to provide an aesthetic appearance to the multi-use garment. The multi-use garment is built in boning and inner bodice construction for full upper body support. The multi-use garment allows a user to wear the garment in its natural form without any panel manipulation and provides support needed to stay on user's body.

The strapless garment can be quickly converted to other designs and can be used as bridal dress and ball gown. The strapless multi-use garment is available in various sizes and colors. The strapless multi-use garment is fabricated from woven cloth to provide comfort to the user. The strapless multi-use garment has simple construction that makes it lightweight and portable.

BRIEF DESCRIPTION OF THE DRAWINGS

FIG. 1A is a front view of the present embodiment, illustrating a front portion of an upper garment portion and a front portion of a gathered skirt of a strapless multi-use garment;

FIG. 1B is a front view of the present embodiment, illustrating a rear portion of the upper garment portion and a rear portion of the gathered skirt of the strapless multi-use garment;

FIG. 2A is a front view of the present embodiment, illustrating a plurality of front panels in a lifted position;

FIG. 2B is a front view of the present embodiment, illustrating the plurality of rear panels in the lifted position;

FIGS. 3A-3B illustrate different designs of the multi-use garment by configuring the plurality of front panels and the plurality of rear panels in different fashionable ways.

FIGS. 3C-3E illustrate alternate embodiments of different designs of the multi-use garment by configuring the plurality of front panels and the plurality of rear panels in different fashionable ways.

DETAILED DESCRIPTION OF THE PREFERRED EMBODIMENT

The following describes example embodiments in which the present invention may be practiced. This invention, however, may be embodied in many different ways, and the description provided herein should not be construed as limiting in any way. Among other things, the following invention may be embodied as methods or devices. As such, the present invention may take the form of an entirely hardware embodiment, an entirely software embodiment, or an embodiment combining software and hardware aspects. The following detailed descriptions should not be taken in a limiting sense.

In this document, the terms "a" or "an" are used, as is common in patent documents, to include one or more than one. In this document, the term "or" is used to refer to a nonexclusive "or," such that "A or B" includes "A but not B," "B but not A," and "A and B," unless otherwise indicated. Furthermore, all publications, patents, and patent documents referred to in this document are incorporated by reference herein in their entirety, as though individually incorporated by reference. In the event of inconsistent usages between this document and those documents so incorporated by reference, the usage in the incorporated

reference(s) should be considered supplementary to that of this document; for irreconcilable inconsistencies, the usage in this document controls.

FIG. 1A is a front view of the present embodiment, illustrating a strapless multi-use garment 10. The strapless multi-use garment 10 comprises an upper garment portion 12 covering an area above waist of a user, a gathered skirt 18 attached with the upper garment portion 12, a waist band 24 attached at a top portion 26 of the gathered skirt 18, a plurality of front panels 28, a plurality of rear panels 30 (FIG. 1B) and at least one fastening means 38 (FIG. 1B).

The upper garment portion 12 includes a front portion 14 and a rear portion 16 (FIG. 1B). The waist band 24 is designed to surround the waist of the user. The gathered skirt 18 includes a front portion 36 and a rear portion 34 (FIG. 1B). The plurality of front panels 28 and the plurality of rear panels 30 (FIG. 1B) extend downwardly from the waist band 24. The plurality of front panels 28 is attached at the front portion 36 of the gathered skirt 18 and the plurality of rear panels 30 is attached at the rear portion of the gathered skirt 34 (FIG. 1B). The plurality of front panels 28 and the plurality of rear panels 30 (FIG. 1B) are adaptable for multiple configurations that allow the multi-use garment 10 to be worn in a wide range of stylish designs. The multiple configurations of the plurality of front panels 28 and the plurality of rear panels 30 (FIG. 1B) allow the strapless multi-use garment 10 to be worn in different occasions. The multi-use garment 10 is built in boning and inner bodice construction for full upper body support. The plurality of front panels 28 includes a front panel end 20 and the plurality of rear panels 30 includes a rear panel end 22 (FIG. 1B). The front panel end 20 and the rear panel end 22 (FIG. 1B) are not attached with the garment 10.

FIG. 1B is a front view of the present embodiment, illustrating the rear portion of the upper garment portion 16 and the rear portion of the gathered skirt 34 of the strapless multi-use garment 10. The multi-use garment 10 includes at least one fastening means 38 extending downwards along the rear portion of the upper garment portion 16 and the rear portion of the gathered skirt 34 to firmly secure the strapless multi-use garment 10 on the user's body. The at least one fastening means 38 may be a zipper. The strapless multi-use garment 10 has simple construction thereby making the garment 10 lightweight and portable.

FIG. 2A illustrates the plurality of front panels 28 in a lifted position. The plurality of front panels 28 is lifted to configure the multi-use garment in different designs. FIG. 2B illustrates the plurality of rear panels 30 in the lifted position. In the preferred embodiment, there are two front panels 28 and two rear panels 30. The plurality of front panels 28 and rear panels 30 are lifted to configure at skirt level and/or at the neckline around shoulders of the user to create a variety of neckline and skirt styles. The plurality of front panels 28 and the plurality of rear panels 30 are pleated to add an aesthetic appearance to the multi-use garment 10. The strapless multi-use garment 10 is available in various sizes and colors.

FIGS. 3A-3B illustrate different designs of the multi-use garment 10 by configuring the plurality of front panels 28 and the plurality of rear panels 30 in different fashionable ways. The multi-use garment 10 does not possess any strap thereby allowing a user to wear the garment 10 as a strapless dress in its natural form without any panel manipulation and provides support needed to stay on user's body. Also, the strapless garment 10 can be quickly converted to other designs. The multi-use garment 10 can be used as bridal dress and ball gown. The gathered skirt 18 is very long and

features a slight A-line shape. The multi-use garment **10** is fabricated from woven cloth to provide comfort to the user. Preferably, woven cloth like chiffon material is used for its fabrication.

FIGS. 3C-3E illustrate alternate embodiments of different designs of the multi-use garment. The waist band **24** hits just above the natural waist with delicate gathers and the multi-use garment **10** is fully lined. The plurality of front panels **28** and the rear panels **30** create alternate necklines and skirt details. The gathered skirt **18** is designed in such a way that it hits above the user's knee. 10

While a particular form of the invention has been illustrated and described, it will be apparent that various modifications can be made without departing from the spirit and scope of the invention. Accordingly, it is not intended that the invention be limited, except as by the appended claims. 15

What is claimed is:

1. A method for wearing a multi-use garment, comprising:
wearing a multi-use garment in one of a first configuration and a second configuration, wherein the multi-use garment comprises:
a strapless upper garment portion;
a gathered skirt formed beneath the strapless upper garment portion; and
at least four panels, each panel of the at least four panels having an end and an opposing end, wherein the end of each panel of the at least four panels is attached to an upper portion of the gathered skirt at an intersecting area of the strapless upper garment portion and the gathered skirt and the opposing end of each panel of the at least four panels is unattached to the gathered skirt, and wherein each of the at least four panels is pleated; 25
wherein wearing the multi-use garment in the first configuration comprises causing the at least four panels to extend downwardly from the intersecting area such that the pleats of each of the at least four panels become a part of the gathered skirt, and wherein an entirety of the strapless upper garment portion is visible when the multi-use garment is worn in the first configuration; and
wherein wearing the multi-use garment in the second configuration comprises:
selecting a first group of at least two panels from the at least four panels;
lifting the first group of at least two panels in a direction above the intersecting area; and
connecting the first group of at least two panels together, wherein a connection formed by the first group of at least two panels is positioned above the strapless upper garment portion. 35
2. A method for wearing a multi-use garment, comprising:
wearing a multi-use garment in one of a first configuration and a second configuration, wherein the multi-use garment comprises:
a strapless upper garment portion;
a gathered skirt formed beneath the strapless upper garment portion; and
a plurality of panels, each panel of the plurality of panels having an end and an opposing end, wherein the end of each panel of the plurality of panels is attached to an upper portion of the gathered skirt at an intersecting area of the strapless upper garment portion and the gathered skirt and the opposing end of each panel of the plurality of panels is unattached to the gathered skirt, and wherein each of the plurality of panels is pleated; 40

wherein wearing the multi-use garment in the first configuration comprises causing the plurality of panels to extend downwardly from the intersecting area such that the pleats of each of the plurality of panels become a part of the gathered skirt, and wherein an entirety of the strapless upper garment portion is visible when the multi-use garment is worn in the first configuration; and wherein wearing the multi-use garment in the second configuration comprises:

selecting a first group of at least two panels from the plurality of panels;
lifting the first group of at least two panels in a direction above the intersecting area;
connecting the first group of at least two panels together, wherein a connection formed by the first group of at least two panels is positioned above the strapless upper garment portion;
selecting a second group of at least two panels of the plurality of panels, wherein the second group is different than the first group;
lifting the second group of at least two panels in a direction toward the intersecting area; and
connecting the second group of at least two panels together, wherein a second connection formed by the second group of at least two panels is positioned at the intersecting area. 45

3. The method of claim 1, wherein the connection is positioned in an area corresponding to a front portion of the multi-use garment.

4. The method of claim 1, further comprising twisting each of the first group of at least two panels such that each of the first group of at least two panels appears narrower prior to connecting the first group of at least two panels together. 50

5. The method of claim 1, wherein the connection is positioned at a location along a midline of the multi-use garment, wherein the midline extends through the strapless upper garment portion and the gathered skirt.

6. The method of claim 1, wherein the ends of the first group of at least two panels are both attached to either a front portion of the gathered skirt or to a rear portion of the gathered skirt. 55

7. The method of claim 1, wherein lifting the first group of at least two panels further comprises moving the opposing end of each of the first group of at least two panels to a side of the strapless upper garment portion and the gathered skirt opposite the end of the first group of at least two panels.

8. The method of claim 1, wherein connecting the first group of at least two panels together further comprises tying the first group of at least two panels into a bow. 60

9. A method for wearing a multi-use garment, comprising:
wearing a multi-use garment in one of a first configuration and a second configuration, wherein the multi-use garment comprises:
a strapless upper garment portion;
a gathered skirt formed beneath the strapless upper garment portion; and
at least four panels, each panel of the at least four panels having an end and an opposing end, wherein:
the end of each panel of the at least four panels is attached to an upper portion of the gathered skirt at an intersecting area of the strapless upper garment portion and the gathered skirt, wherein a first set of the at least four panels is attached to a front portion of the gathered skirt and wherein a second set of the at least four panels is attached to a rear portion of the gathered skirt; 65

the opposing end of each panel of the at least four panels is unattached to the gathered skirt, wherein wearing the multi-use garment in the first configuration comprises causing each panel of the at least four panels to extend downwardly from the intersecting area to become a part of the gathered skirt, and wherein an entirety of the strapless upper garment portion is visible when the multi-use garment is worn in the first configuration; and wherein wearing the multi-use garment in the second configuration comprises:

selecting at least one panel from the first set of the at least four panels that are attached to the front portion of the gathered skirt and at least one panel from the second set of the at least four panels that are attached to the rear portion of the gathered skirt;

lifting the at least one panel from the first set of panels and the at least one panel from the second set of panels in a direction above the intersecting area; and

connecting the at least one panel from the first set of panels and the at least one panel from the second set of panels together, wherein a connection formed by the at least one panel from the first set of panels and the at least one panel from the second set of panels is positioned above the strapless upper garment portion.

10. The method of claim 9, wherein the connection is positioned in an area corresponding to a front portion of the strapless upper garment portion.

11. The method of claim 9, further comprising twisting the at least one panel from the first set of panels and the at least one panel from the second set of panels such that each of the panels appears narrower prior to connecting the at least one panel from the first set of panels and the at least one panel from the second set of panels together.

12. The method of claim 9, wherein the connection is positioned at a location along a midline of the multi-use garment, wherein the midline extends through the strapless upper garment portion and the gathered skirt.

15 13. The method of claim 9, wherein lifting the at least one panel from the first set of panels further comprises moving the opposing end of each of the at least one panel from the first set of panels to a side of the strapless upper garment portion and the gathered skirt opposite the end of the at least one panel from the first set of panels.

20 14. The method of claim 9, wherein connecting the at least one panel from the first set of panels and the at least one panel from the second set of panels together further comprises tying the at least one panel from the first set of panels and the at least one panel from the second set of panels into a bow.
